US00D902293S

(12) **United States Design Patent** (10) Patent No.: **US D902,293 S**
(45) Date of Patent: **** Nov. 17, 2020**

(54) **EYEGLASSES**

(71) Applicant: **Dolby Laboratories Licensing Corporation**, San Francisco, CA (US)
(72) Inventors: **Douglas J. Gorny**, Pacifica, CA (US); **Andrew John Healy**, San Francisco, CA (US); **Thao D. Hovanky**, San Francisco, CA (US); **Barret Lippey**, Foster City, CA (US); **Matthew York Sugarman**, Redondo Beach, CA (US)

(73) Assignee: **Dolby Laboratories Licensing Corporation**, San Francisco, CA (US)

(**) Term: **15 Years**

(21) Appl. No.: **29/715,872**

(22) Filed: **Dec. 5, 2019**

Related U.S. Application Data

(63) Continuation of application No. 29/637,318, filed on Feb. 15, 2018, now Pat. No. Des. 872,793.

CLAIM

The ornamental design for eyeglasses, as shown and described.

DESCRIPTION

FIG. 1 is a front perspective view of eyeglasses showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines illustrate portions of the eyeglasses which form no part of the claimed design.

1 Claim, 6 Drawing Sheets
